UNITED STATES PATENT OFFICE.

ROBERT M. DIXON, OF EAST ORANGE, NEW JERSEY, ASSIGNOR TO THE SAFETY CAR HEATING & LIGHTING COMPANY, A CORPORATION OF NEW JERSEY.

GENERATOR SUSPENSION.

1,167,389.

Specification of Letters Patent. Patented Jan. 11, 1916.

Application filed February 16, 1911. Serial No. 609,055.

REISSUED

To all whom it may concern:

Be it known that I, ROBERT M. DIXON, a citizen of the United States, residing at East Orange, in the county of Essex and State of New Jersey, have invented certain new and useful Improvements in Generator Suspension, of which the following is a full, clear, and exact description, such as will enable other skilled in the art to which it applies to make and use the same.

This invention relates to the mounting of generators to be driven from car-axles.

One of the objects of the invention is to provide a practical and efficient device of the character described in which the parts are readily assembled and securely held in position and are adapted to give an even and reliable drive to the generator.

Another object of the invention is to provide a device of the character described which shall be compact, cheap, and simple in construction, and readily adjustable to meet various conditions of use.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of the invention, Figure 1 represents a plan view of the invention in connection with a car-truck. Fig. 2 represents a side elevation thereof; and Fig. 3 represents a rear end elevation thereof.

40 The device, as shown in the drawings, is preferably attached to a car-truck which may be of any standard type. Generally speaking, the arrangement of parts as shown in the drawings is as follows:—A truck supports a fixed frame, which in turn supports a sliding frame or carriage upon which is mounted a dynamo adapted to be driven through suitable connections by an axle of the car-truck.

50 The fixed frame consists of projecting arms 1, preferably attached to the side sills 2 of the truck; and cross-bar 3. The cross-bar occupies a position below the arms and its extremities are curved upwardly to meet the arms, to which they are preferably riv-

eted. The sliding carriage, mounted on the projecting arms, comprises a pair of side bars 4 each of the side bars being adapted to bear throughout its length and to slide on one of the projecting arms. It also includes a pair of parallel depending members each of which comprises a pair of hanger links 5 situated on opposite sides of the frame and a cross-rod 6 attached at the lower portion of these hanger links. Each of the links is pivotally attached by a bolt 7 to one of the side bars at a point preferably above the projecting arms. Each cross-rod 6 passes through the oppositely disposed hanger links 5 and its ends are threaded and are secured to the hanger links by nuts 8. The cross-rods may be removed from the hanger links by unfastening these nuts. The motion of the side-bars is guided by means of plates 9 attached upon either side thereof and extending downward in such position that they straddle each of the arms.

As shown in Fig. 1, each of the hanger links consists of two upright bars which are riveted together in such manner that a space is provided therebetween, and through this space the projecting arms pass. It will be noted that any lateral thrust given to the carriage will be substantially compensated by contact of the bars of the hanger links with the projecting arms.

The projecting arms are braced to withstand vertical as well as lateral movement by means of diagonal braces 10 attached to the end sill 11 of the car-truck. As will be noted, the braces are rigidly attached to the end-sill and are so secured to the movable carriage that the latter may be moved longitudinally with respect to the arms. This longitudinal movement is permitted by slots 12 formed in the guide plates 9, through which pass bolts 13 adapted to retain the carriage at any desired position with respect to the brace. The carriage is additionally secured by bolts 14 associated with slots 15, also adapted to permit longitudinal movement of the carriage.

Mounted upon the lower cross-rods 6 is the dynamo 16 which is adjustable laterally and horizontally as hereinafter described. The dynamo is provided with lateral lugs 17 through which the cross-rods pass. The lugs are adapted to loosely support the dynamo so that it may rotate about the rods and thus maintain a substantially level po-

sition. Between each pair of lugs a collar 18 is placed which is rigidly secured to the cross-rods by bolts 19 and serves to hold the dynamo in a desired position. In order to laterally adjust the dynamo the collars are loosened and the dynamo may then be moved along the cross-rods into a given position. The horizontal adjustment of the dynamo is automatically accomplished by the oscillating motion of the links of the movable carriage, which is provided with a single tension rod 20 and spring 21 adapted to properly position the dynamo and to secure uniform tension of the belt. The tension rod 15 is attached to the rear cross-rod, as shown, and passes through the rigid cross-bar 3 of the fixed frame (see Fig. 1). On the outside of the cross-bar one end of the spring 20 is attached, the other end abutting a gravity nut 22, whose position is adapted to be adjusted with respect to the tension rod by means of a threaded portion upon the end of the rod. The rod and spring will tend to restrain any slight movement in the movable 25 frame, but in order to prevent unusual swinging to and fro of the frame, incident to severe bumping together of cars or inequalities in the roadbed, chains 23 are provided which are secured to the end sill 11 30 of the car truck and to the forward cross-rod.

In order to provide a means for horizontally adjusting the movable frame with respect to the arms of the fixed frame and at the same time for horizontally adjusting the position of the dynamo, a threaded bolt 24 is provided on each side of the sliding carriage which passes through a perforation 25 at either extremity of the cross-bar 3 and 35 is held in position by lock nuts 26. The bolt also passes through and is secured to an offset portion 27 on each of the side bars. Through the operation of the lock nuts and associated parts the movable carriage may 40 be forced backward or forward upon the arms.

As shown in the drawings, the dynamo is so positioned with respect to the cross-rods that the axis of its armature shaft 28, upon 45 which is mounted the pulley 29, is below the line adjoining the centers of the cross-rods and is substantially in line with the center line of the car-truck axle 30, upon which is mounted the pulley 31 adapted 50 to transmit motion to pulley 29 by belt 32. This method of positioning the dynamo insures a substantial and compact construction.

The device described is positive in its action; possesses simple parts and is well adapted to stand the wear incident to its intended location. It is, furthermore, inexpensive and may be readily assembled and disassembled.

60 65 The provision of means whereby the dy-

namo is maintained in a substantially level position serves to prolong the length of life of the belt connecting the dynamo pulley and the axle pulley, for there is substantially a uniform tension upon the belt at all times, 70 and also secures a steady supply of oil from the dynamo oil cups, which are also maintained in a level position. The means for mounting the sliding carriage and its hanger links secures the advantage that relatively 75 long links may be used with a fixed height of dynamo and a given clearance below the lower sill of the car frame, and hence with a given swing of the generator there is a minimum elevation of its position. In other 80 words the movement of the generator is nearly directly toward and away from the driving pulley of the axle. The sliding carriage, as shown, is easily adjustable and its side bars, bearing throughout their length 85 upon the projecting arms minimize the tendency to bruise these projecting arms under jar and vibration. Moreover the sliding carriage and the hanger links constructed as shown are well adapted to resist any lateral 90 thrust or tendency of the generator to swing sidewise of the truck, and there is small liability of breakage or wear in these parts. By providing a single tension device positioned substantially opposite the dynamo 95 pulley the tendency to bend the cross-rod is practically obviated inasmuch as the pull of the belt and the pull of the spring are substantially opposed. There is, further, little chance to pull the cross-rod out of parallelism with respect to the car truck axle. By 100 the use of separate lower cross-rods the generator may be easily mounted or dismounted therefrom as for purposes of repair, and if one rod becomes bent it may be readily removed and another substituted therefor, using the same hanger links.

It will thus be seen that a simple device is provided wherein the objects of the invention are achieved.

As many changes could be made in the above construction and many apparently widely different embodiments of this invention could be made without departing from the scope thereof, it is intended that all matter contained in the above description or 115 shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might 120 be said to fall therebetween.

Having described my invention, what I claim as new and desire to secure by Letters Patent, is:

1. In an apparatus of the character de- 130

- scribed, in combination, a car-truck, a dynamo provided with lugs, a frame projecting from said truck, side bars adjustably mounted on said frame, links pivotally attached to each of said side bars, and cross rods removably attached to said links and passing through said lugs.
2. In an apparatus of the character described, in combination, a car-truck, a dynamo provided with lugs on opposite sides, a frame projecting from said truck, side bars adjustably mounted on said frame, a pair of links pivotally attached to each of said side bars, and a pair of cross rods removably attached to said links and passing through the lugs on said dynamo.
3. In an apparatus of the character described, in combination, a car truck, a dynamo, a frame projecting from said truck, members adjustably mounted on said frame, links pivotally attached to said members, cross rods attached to said links, and means for supporting said dynamo on said cross rods in such a manner that it cannot be removed therefrom without removing said rods from said links.
4. In an apparatus of the character described, in combination, a car truck, a dynamo, a frame comprising members projecting from said truck and connected at their ends by a cross bar, side bars adjustably mounted on said projecting members, links pivotally attached to said side bars, rods detachably connected to said links, means for supporting said dynamo upon said rods, and a single tension spring attached to said cross bar and to one of said rods.
5. In an apparatus of the character described, in combination, a car-truck, arms projecting therefrom, a sliding carriage mounted on said arms and adapted to support a dynamo, said carriage comprising side bars, each of said side bars being adapted to slide on one of said arms, hanger links pivotally attached to each of said side bars at a point above said arms and cross rods attached to said hanger links and adapted to be removed therefrom.
6. In an apparatus of the character described, in combination, a car-truck, a fixed frame attached thereto comprising arms projecting from the sides of said car-truck and a cross bar connecting said arms, a movable carriage adapted to support a dynamo, said carriage being mounted on said arms and comprising side bars adapted to slide upon said arms, hanger links pivotally attached to each of said side bars at a point above said arms and cross rods attached to said hanger links and adapted to be removed therefrom, and a tension spring associated with said cross bar and said cross rod adapted to restrain the motion of said movable carriage.
7. In an apparatus of the character described, in combination, a car-truck, arms projecting therefrom, a sliding carriage mounted on said arms and adapted to support a dynamo, said carriage comprising side bars each of said side bars being adapted to bear throughout its length and to move on one of said arms, and a pair of parallel depending members, each of said members comprising a pair of hanger links and a cross-rod attached to said links each of said links being pivotally attached to one of said side bars at a point above said projecting arms.

In testimony whereof I affix my signature, in the presence of two witnesses.

ROBERT M. DIXON.
